UNITED STATES PATENT OFFICE.

MAX J. LIEBENSTEIN, OF CHICAGO, ILLINOIS, ASSIGNOR TO A. STEIN & COMPANY, OF CHICAGO, ILLINOIS, A CORPORATION.

DESIGN FOR A GARTER.

49,391.

Specification for Design.

Patented July 18, 1916.

Application filed February 1, 1915. Serial No. 5,574. Term of patent 3½ years.

To all whom it may concern:

Be it known that I, MAX J. LIEBENSTEIN, a citizen of the United States, residing in the city of Chicago, State of Illinois, have invented a new, original, and ornamental Design for Garters, of which the following is a specification, reference being had to the accompanying drawing, forming part thereof.

The figure is a front view of a garter

showing my new design, part of the band of the garter being shown as folded upon itself.

I claim:

The ornamental design for a garter as shown.

MAX J. LIEBENSTEIN.
